Primary Examiner — John R Yeh*Assistant Examiner* — Dustin Andrew Griffith(57) CLAIM

The ornamental design for a diaper bag, as shown and described.

DESCRIPTION

FIG. 1 is a perspective view of a diaper bag design showing my new design.

FIG. 2 is a front view of a diaper bag.

FIG. 3 is a rear view of a diaper bag.

FIG. 4 is a left side view of a diaper bag.

FIG. 5 is a right side view of a diaper bag.

FIG. 6 is a top view of a diaper bag; and,

FIG. 7 is a bottom view of a diaper bag.

The broken lines in the drawings depict portions of the diaper bag that form no part of the claimed design.
